UNITED STATES PATENT OFFICE

2,111,104

AIR CONDITIONER

Samuel Slutsky, South Bend, Ind.

Application November 16, 1936, Serial No. 111,097

3 Claims. (Cl. 257—9)

This invention relates to air conditioners and an object of the present invention is to provide a device which may be used as an air cooler, or as a heating unit, or for conditioning heated air as it enters a room or the like from a furnace or analogous heating plant.

The invention together with its objects and advantages will be best understood from a study of the following description taken in connection with the accompanying drawings wherein:

Figure 1 is a front elevational view of the device.

Figure 2 is an end elevational view thereof.

Figure 3 is a sectional view taken substantially on the line 3—3 of Figure 1.

Figure 4 is an elevational view of the device with the door at the front of the device removed.

Figure 5 is a view taken substantially on the line 5—5 of Figure 2.

Figure 6 is a vertical sectional view through a coil assembly.

Figure 7 is a side elevational view of the coil.

Figure 8 is a detail sectional view taken substantially on the line 8—8 of Figure 5, and

Figure 9 is an enlarged fragmentary view partly in section and partly in elevation illustrating a slightly modified form of the invention.

Referring more in detail of the drawings it will be seen, that in the preferred embodiment of the invention, there is provided a casing 5 having a bottom 6, rear wall 7, end walls 8, top wall 9, and a bodily removable front door 10.

Supported between the end walls 8 of the cabinet or casing are angle bars 11, 12, which support a pan or tray 13 hereinafter more fully referred to.

Above the cleats 11 and 12 there is suitably supported in the upper portion of the cabinet 5 a horizontal partition 14 providing in the upper portion of the cabinet a chamber 15.

Provided on the cleat 11 and on the forward edge of the partition 14 are strips 16 of rubber, felt, or other suitable yielding material, against which the inner face of the door 10 bears to provide sealing joints between the door 10 and the cleat 11 on the one hand, and the door 10 and the partition 14 on the other hand.

Suitably arranged in the bottom of the cabinet 5 is a compressor 17 which includes among other parts a motor 18 for driving the compressor.

The compressor 17 is of a water-cooled type and the water jacket of the compressor is connected in any suitable manner with a water supply line or pipe 19. The water return line for the com-

pressor is indicated by the reference numeral 20.

The condensing fluid, which may be of any suitable type, is contained within a suitable tank 21 that is connected with the compressor 17 through the medium of a conduit 22.

Supported by the pan 13 adjacent one end of the pan is a refrigerant coil 23, and one of the headers of the coil 23, as shown in Figures 7 and 8, has its outer wall pressed inwardly as at 24 to provide a partition for the header which will serve to so direct the refrigerant flowing through the header as to insure the passage of the refrigerant through each and every one of the tubes 25 that connect the headers of the coil.

The refrigerant tank 21 is connected with the 15 said one header of the coil 23 through the medium of a conduit or piping 26 while the compressor 17 is connected to said one header of the coil 23 through the medium of piping or a conduit 27. Thus it will be seen that provision is made for a 20 close circuit connection involving compressor 17, tank 21 and the coil 23 so that the liquid refrigerant will flow to and from the coil.

Suitably arranged within the conduit or piping 26 is an expansion valve 28 controlled by a thermostatic 25

For controlling the passage of air through the coil 23 from one side of the latter to the other, there is hingedly mounted at one side of the casting housing the coil 23 a damper or door 30, suitable means indicated generally at 31 being provided for securing the damper or door 30 at the desired position of adjustment.

The partition 14, as clearly shown in Figure 5, is provided with an opening 32 and located immediately below the opening 32 is a suction fan 33 of suitable construction and design. The shaft for the fan 33 is journaled in bearing brackets 34 suspended from the partition as shown.

For driving the fan 33 there is mounted on the partition 14 within the compartment 15 an electric motor 35 that has a belt and pulley drive connection 36 with the shaft of the fan 33 as shown in Figure 5.

Also, each end wall 8 of the casing or cabinet 5 is provided adjacent the bottom thereof with air inlet openings 37. For these openings 37 there are provided at the inner sides thereof screens or filtering elements 38. Also for the 50 openings there are provided hinged dampers 39.

There is also provided in the top 9 of the cabinet or casing 5 an air exhaust opening 40 and for this opening 40 there are provided pivoted damper plates 41.

Also, if desired, and as shown, door 10 may be provided with an air exhaust opening 42 for which there are also provided pivoted damper plates 43.

From the description of the invention thus far it will be seen that with the fan 23 in motion air will be drawn into the openings 37 in the end walls of the cabinet passing upwardly of the cabinet through the space between one end of the pan or tray 13 and the adjacent end wall 8 of the cabinet at the left side of the cooling coil assembly 23. With the damper door 39 of the cooling coil assembly in open position it will be further appreciated that the air will pass through the coil assembly to be cooled, the cold air passing upwardly through the opening 32 and out into the room through the opening 40 in the top 9 of the cabinet and the opening 42 in the door 10 of the cabinet for lowering the room temperature. Thus it will be seen that the device will serve admirably for conditioning and cooling the air of a room or the like.

Further the invention comprehends the provision of a second coil assembly 44 including an outer frame-like casing in which are arranged oppositely disposed headers connected by circulating tubes, and this coil assembly, when used, is supported on the pan 13 at the end thereof remote from the coil 23.

Connected to the inlet of one of the headers 30 of the coil 44 is a supply pipe 45 while a return pipe 46 is connected to the outlet of said header of the coil assembly 44.

Arranged in the pipe 45 is a valve 47 while pipe 19 is connected with pipe 45 between the 35 coil 44 and the valve 47 through the medium of piping 48 in which is arranged a valve 49.

It will thus be seen that when it is desired to make use of coil 44 as an auxiliary to coil 23 for cooling the air passing through the cabinet 5 40 valve 47 is closed and valve 49 open so that cold water from the source of supply will pass from the piping 19 through the valve 49 and piping 48 to circulate through the coil assembly 44.

Coil assembly 44 is also provided at one side 45 thereof with a hinged damper or door 50, means 51 being provided for securing the door 50 at the desired adjustment. Thus with door 50 in an open position some of the air circulating through the casing 5 will pass upwardly of the casing and 50 through the coil assembly 44 from the left to the right of the assembly to pass with the air cooled by the coil 23 upwardly through the opening 32 to exhaust into the room through the openings 40 and 42.

55 The pipe 45 is provided for connecting the coil 44 with a domestic hot water or steam heating system so that the device may be used in the nature of a heater for heating air as it passes through the device into a room for raising the 60 temperature of the room. In this connection it will be appreciated that when the device is so used the cooling apparatus associated with the device is inactive and with valve 49 closed and valve 47 open hot water or steam as the case may 65 be will flow through the pipe 45 from the source of supply and through the coil assembly 44 to return to the source through the pipe 46. Thus it will be seen that air entering the casing through the openings 37 and flowing upwardly 70 through the coil assembly 44 will be heated, the heated air passing upwardly through the opening 32 and into a room or the like through the openings 40 and 42 for raising the temperature of the room.

75 Referring particularly to Figure 9 it will be

seen that the casing 5 as therein illustrated is provided in the bottom 6 thereof and adjacent one of the end walls 8 with an opening 52 that is to be placed over a floor register or the like.

Internally the casing 5 is also provided in proximity to the opening 52 with vertical walls 53 and a horizontal wall 54 which provide an air intake compartment into which the hot air passing through the register enters.

Wall 53 is provided with an opening 55 over 10 which is disposed a filtering element in the form of a screen or the like 56. Also for the opening 55 there are provided pivoted damper plates 57.

It will thus be seen that with the fan 23 in operation the hot air passing into the chamber 15 56 will pass through the opening 55 and upwardly through the casing 5 into the room to be heated through the openings 40 and 42.

For moistening the heated air thus passing into the casing there is provided a suitable spray 20 nozzle 59 that extends upwardly above the pan 13 and is connected with the pipe 19 through the suitable pipe connections 60. In the piping 60 is a valve 61.

Obviously, the water from the spray nozzle 59 25 will tend to settle in the tray 33 and the hot air passing upwardly through the device will become moistened by contact with the water prior to the entrance of the heated air into the room.

It will also be understood and appreciated that 30 pan 33 will catch the drippings from the coils 23 and 44 as well as the water from the spray nozzle 59. The water collecting in the pan 13 will drain therefrom through the medium of a drain pipe 61 that extends downwardly from the pan and outwardly of the casing through a suitable opening 35 provided therefor in an end wall 8 of the casing or cabinet 5.

It is thought that a clear understanding of the 40 construction, utility and advantages of a device of this character as well as the many uses to which the same may be put will be had by those skilled in the art without a further detailed description thereof.

Having thus described the invention what is 45 claimed as new is:—

1. In a device of the character described, a cabinet having a bottom wall, end walls, a rear wall, a top wall, and a bodily removable front door, said cabinet having in the end walls thereof adjacent the bottom of the cabinet air inlet openings, and in the top walls, and also in said bodily removable door at the top of the latter air exhaust openings, tray supporting means in the 50 cabinet above the bottom of the cabinet, a tray mounted on said supporting means, said tray at its respective opposite ends terminating short of the end walls of the cabinet, coil assemblies supported by the tray adjacent the respective opposite ends of the tray, a power driven fan mounted in the cabinet above said tray and between said coil assemblies said fan serving to draw air into the casing through the openings in the end walls of the casing and to force said air through the 55 openings in the top of the cabinet and the bodily removable door of the cabinet, one of said coils being adapted to have a refrigerant medium circulated therethrough for cooling the air passing through the cabinet, and the other of said coils 60 adapted to have either cold water circulated therethrough whereby the second coil assembly may be used as an auxiliary air-cooling medium, or to have a heating medium such as steam, hot water, etc., circulated therethrough whereby said 65 70 75

second coil may be used as a heating medium, optionally.

2. In a device of the character described, a cabinet having a bottom wall, end walls, a rear wall, a top wall, and a bodily removable front door, said cabinet having in the end walls thereof adjacent the bottom of the cabinet air inlet openings, and in the top walls, and also in said bodily removable door at the top of the latter air exhaust openings, tray supporting means in the cabinet above the bottom of the cabinet, a tray mounted on said supporting means, said tray at its respective opposite ends terminating short of the end walls of the cabinet, coil assemblies supported by the tray adjacent the respective opposite ends of the tray, a power driven fan mounted in the cabinet above said tray and between said coil assemblies, said fan serving to draw air into the casing through the openings in the end walls 20 of the casing and to force said air through the openings in the top of the cabinet and the bodily removable door of the cabinet, one of said coils being adapted to have a refrigerant medium circulated therethrough for cooling the air passing through the cabinet, and the other of said coils adapted to have either cold water circulated therethrough whereby the second coil assembly 25 may be used as an auxiliary air-cooling medium, or to have a heating medium such as steam, hot water, etc., circulated therethrough whereby said second coil may be used as a heating medium, optionally, each of said coils including a hinged baffle at one side thereof and means associated with the coil and the baffle for holding the latter in the desired position of adjustment.

3. In a device of the character described, a cabinet having a bottom wall, end walls, a rear wall, a top wall, and a bodily removable front

door, said cabinet having in the end walls thereof adjacent the bottom of the cabinet air inlet openings, and in the top walls, and also in said bodily removable door at the top of the latter air exhaust openings, tray supporting means in the cabinet above the bottom of the cabinet, a tray mounted on said supporting means, said tray at its respective opposite ends terminating short of the end walls of the cabinet, coil assemblies supported by the tray adjacent the respective opposite ends of the tray, a power driven fan mounted in the cabinet above said tray and between said coil assemblies, said fan serving to draw air into the casing through the openings in the end walls of the casing and to force said air through the openings in the top of the cabinet and the bodily removable door of the cabinet, one of said coils being adapted to have a refrigerant medium circulated therethrough for cooling the air passing through the cabinet, and the other of said coils adapted to have either cold water circulated therethrough whereby the second coil assembly 30 may be used as an auxiliary air-cooling medium, or to have a heating medium such as steam, hot water, etc., circulated therethrough whereby said second coil may be used as a heating medium, optionally, each of said coils including a hinged baffle at one side thereof and means associated with the coil and the baffle for holding the latter in the desired position of adjustment, said cabinet also having an opening in the bottom thereof adapted to be positioned over a floor register whereby warm air from a hot air heating system may pass through the cabinet, and a spray device mounted in the cabinet above 35 said pan for use in humidifying air passing through the cabinet.

SAMUEL SLUTSKY.
